UNITED STATES PATENT OFFICE.

ISADORE JOSEPH LEVY, OF NEW YORK, N. Y.

DESIGN FOR A HAND-BAG.

No. 39,938.

Specification for Design.

Patented April 20, 1909.

Application filed February 13, 1909. Serial No. 477,821. Term of patent 3½ years.

To all whom it may concern:

Be it known that I, ISADORE JOSEPH LEVY, a citizen of the United States, and a resident of New York, in the county and State of New York, have invented a new, original, and ornamental Design for Hand-Bags, of which the following is a specification, reference being had to the accompanying drawing, forming a part hereof.

The figure is a perspective view of a hand bag showing my design.

This invention relates to an ornamental design for the sides of a hand or traveling bag. The sides of the bag comprise a base having a straight lower edge and having a raised border around its upper and outer edges, which edges are formed in a combination of straight and curved lines, as shown in the accompanying drawing.

I claim—

The ornamental design for a hand bag as shown and described.

ISADORE JOSEPH LEVY.
